UNITED STATES PATENT OFFICE.

CLYDE P. EVANS, OF ST. LOUIS, MISSOURI.

LAPSED-TIME-CALCULATING MACHINE.

1,377,620.

Specification of Letters Patent.

Patented May 10, 1921.

Application filed June 24, 1918. Serial No. 241,631.

To all whom it may concern:

Be it known that I, CLYDE P. EVANS, a citizen of the United States, residing at the city of St. Louis, State of Missouri, have 5 invented a certain new and useful Improvement in Lapsed-Time-Calculating Machines, of which the following is a full, clear, and exact description, such as will enable others skilled in the art to which it appertains to 10 make and use the same, reference being had to the accompanying drawings, forming part of this specification, in which—

Figure 1 is a plan view of the base member of my improved device.

Fig. 2 is a vertical longitudinal sectional view through the same.

Fig. 3 is a detail view showing the underside of the movable indicating member.

Fig. 4 is a partial plan view of the parts 20 assembled.

Fig. 5 is a detail view of the movable indicator supporting member inverted.

Fig. 6 is a detail view of the indicator.

Fig. 7 is a vertical sectional view through 25 a modified form.

Fig. 8 is a detail view of another modified form.

This invention relates to a new and useful improvement in lapsed time calculating devices employed for the purpose of determining the cost of labor on a given job of work at a certain rate per hour depending upon the length of time spent on the job.

The object of my present invention is to 35 simplify the construction of devices of this character, cheapen the cost of production thereof, and to make the same accurate and dependable in determining the cost of labor on any given job and at a predetermined 40 rate per hour, the number of hours or time spent on the job being known,—in this way saving mental and arithmetical computations usually resorted to in the cost departments where pencil and paper are generally employed in making the computations.

In the drawings, 1 indicates a base or bed plate (see Fig. 1) at the righthand end of which is a table like extension 2 whose upper surface is countersunk for the reception 50 of a removable card 3, said card being held in position by spring clips 4. In this card, in suitable lined spaces arranged in horizontal and vertical columns, are previously ascertained calculations of hours and frac-

tions of hours of time multiplied by a given 55 rate per hour.

In the instance illustrated in Fig. 1, the rate per hour is sixty cents (60¢) and according to my present disclosure the hour is divided into fractions of five minutes or 60 one-twelfth hour. It is obvious, however, that this scale could be changed according to the design of the maker by dividing the hour into ten multiples, or such other multiple as occasion requires.

The card 3 illustrated in Fig. 1 also has a day rate printed thereon, preferably at the righthand corner, to indicate the cost per day of a given number of hours for a certain piece of work; for instance, if the 70 work was started Monday and finished on Wednesday, three full days of nine hours each, multiplied by the day rate of five dollars and forty cents (\$5.40), the sum total of the cost of the job would be sixteen dollars 75 and twenty cents (\$16.20), this amount being determined at the beginning of the morning of the next succeeding working day when time on the job is usually taken and ascertained. For Saturdays or half holidays, 80 the same computation is carried out wherein five and one-half (5½) hours is computed as constituting a half-day's work. This day schedule is also employed to determine the amount applicable to a piece of work begun 85 early on one day and finished later on another. The day rate to be used in conjunction with the shifting apparatus is as follows: Taking for instance a piece of work begun at 9:10 Monday morning and finished at 2:35 Wednesday afternoon, the computation would be made by combining the value of the time in whole days which had elapsed together with the value of the time in hours or minutes. The hour and minute value for the first partial day is determined by the shifting apparatus herein-after explained. The value of the whole days elapsed is determined by referring to the day schedule in the right hand corner 90 of card 3.

In the example under consideration, Tuesday is the only full day, and hence the cost of the work done on this day is to be added to the cost of the work done on the partial days, i. e. Monday and Wednesday. The cost of the work done on Wednesday is ascertained in the same way as the cost of the 100

partial day's work on Monday is ascertained.

As the work in the example under consideration was commenced at 9:10 a. m. Monday, we will assume, for purposes of illustration, that work on this particular job was stopped at 12 m. and thirty (30) minutes allowed for lunch, work again commencing at 12:30, and stopping at 5 p. m., the quitting time.

From 9:10 a. m. to 12 m. is two hours and fifty minutes, the cost of which, at sixty cents (60¢) per hour, is \$1.70. From 12:30 p. m. until 5 p. m., four hours and thirty minutes, at 60¢, would amount to \$2.70, and the indicator 13^d hereinafter described would point to \$4.70 and, after deducting the thirty (30) minutes for lunch, or lost time, the figure to the right of 13^d on the scales 13^b or 13^c would point to \$4.40, the cost of labor devoted to the job on Monday, on which seven (7) hours and twenty (20) minutes were spent at the rate of 60¢ per hour.

25 In computing the work done on the job on Wednesday, we will assume that work started at 7:30 a. m. and was stopped at 12 m. for lunch, this time being four and one-half hours; from 12:30 to 2:35, two hours and five minutes will have been spent on the work and this added to the four and one-half hours devoted to the job in the morning, would make six (6) hours and thirty-five (35) minutes, devoted to the job on 35 Wednesday. At sixty cents (60¢) an hour, this would amount to \$3.95, thus the total cost of the job for the partial days spent thereon on Monday and Wednesday, and the full day spent thereon on Tuesday, would 40 be \$13.75.

Space or spaces may be provided for ten hour days, eight hour days, or such other hours as may be required in different institutions as constituting a day's work.

45 There are provided, of course, a set of cards for each calculator figured on the basis of different rates per hour, such as various factories require, and these different cards are employed preferably by grouping the 50 number of men working at the same rate per hour and calculating their time by the use of the same card and then changing the card to calculate the next group working at a different rate per hour.

55 It will be seen in this connection that not only is the cost of labor on a given job readily obtainable, but the pay-roll can at the same time be made.

60 Preferably to the left of the table 2, just above described, the surface of the base or bed plate 1 is formed with grooves or kerfs 6 which are arranged at right angles to each other, said grooves or kerfs intersecting each other at the lower right hand end of the bed plate. Opposite the transversely disposed

grooves or kerfs are numbers in the table 7 indicating hours from 7 a. m. to 5 p. m. respectively. These numbers read from right to left, as shown, while opposite the ends of the longitudinally disposed grooves or kerfs 70 is a minute scale 8, reading upward from zero in multiples of five minutes to fifty-five minutes.

The numeral 9 indicates a starting indicator comprising a support also provided with 75 transversely and longitudinally disposed grooves or kerfs 10. This support at its lower or forward edge is provided with a scale 11 containing numbers opposite the transversely disposed grooves or kerfs 10 80 reading from left to right to indicate the hours from 7 a. m. to 5 p. m.

For the sake of distinction, I prefer to distinguish the numbers in the scales 7 and 11 by making the p. m. numbers in heavy black 85 type and the a. m. numbers in open face type, or shading that portion of the scale containing the p. m. numbers, as shown on the drawings.

It will be observed that the numbers on 90 scale 11 are reversely arranged with respect to the numbers on scale 7.

12 indicates a scale at the righthand side or edge of the indicator support containing 95 minute indicating numerals from zero opposite the uppermost longitudinally disposed groove or kerf 10 in multiples of five minutes downwardly, to fifty-five (55), which latter is opposite the foremost longitudinally disposed groove or kerf 10. These 100 minute indicating numerals on scale 12 are reversely arranged with respect to the minute indicating numerals on scale 8.

Two of the edges of the supporting member 9, preferably the foremost and right-hand edge, are provided with depending flanges 9^a which are designed to be fitted in the kerfs 6 of the base plate and thereby securely hold, against accidental displacement, the said support element 9 in its adjusted position.

The numeral 13 indicates a "finish" indicating element whose body portion in the form of a block is provided with depending angularly disposed projections 13^a which are 115 designed to fit in the kerfs or grooves 10 of the supporting element 9, thereby fixing the indicator in its different adjusted positions and holding it in such adjusted positions against accidental displacement. The "finish" indicating element comprises the body portion, just above described, and extending from the right hand end thereof is a stem portion from the extremity of which extend angularly arranged scale portions 13^b and 13^c in opposite directions, while in line with the stem portion is a pointing projection 13^d.

The scales on the oppositely extending portions 13^b and 13^c indicate minutes reading upwardly in multiples of five minutes, 130

the purpose of these scales being to enable the operator to deduct any fraction of an hour from the amount indicated by the pointer 13^d. The object in providing the indicator with two sets of scales 13^b and 13^c is to enable either scale to be employed in making deductions for lost time in the event that in the adjustment of the parts one of said scales 13^b and 13^c projects beyond the margin of the computing card. This is shown in Fig. 4, wherein it will be seen that the scale 13^c projects forwardly beyond the numbers in the spaces in the hour and minute value spaces on card 3. Thus, as shown, the deductions reading from "5" to "25" on scale 13^c cannot be read in connection with any number on card 3. All of the deductions in scale 13^b, however, are opposite numbers on card 3, and thus are readable in connection therewith.

Referring now to Fig. 4, we will assume, in describing the operation of the device, that the workmen started on a particular job at 9:10 a. m.; the supporting element 9 is adjusted so that its indicating arrow A points to the intersection of the grooves or kerfs 6 in the bed plate 1 opposite or in line with the numeral 9 in the a. m. portion of the hour scale 7, and the numeral 10 opposite the longitudinally disposed groove or kerf in the minute scale 8. This adjustment of the indicator supporting element 9 represents the time at which the workmen commenced. Assuming that the particular job, the cost of which is being ascertained, was finished at 2:35 p. m., the indicator 13 will be adjusted so that its arrow B is located at the point of intersection of the kerfs or grooves 10, leading from the p. m. numeral "2" in scale 11, and the kerf leading from the minute indicating numeral "35" in scale 12. This will locate the pointer 13^d so as to indicate three dollars and twenty-five cents (\$3.25), being the labor cost of the particular job being computed for the time lapsing from the indicated time of starting said job to the indicated time when said job was completed. This computation is based on the rate of sixty cents (60¢) per hour. If the workman on the particular job under consideration had lost forty minutes from the job for lunch, or for any other reason, the operator would refer to scale 13^b or 13^c, and accept the numbers to the right of the numeral "40" as the actual cost of the job, in this instance, two dollars and eighty-five cents (\$2.85).

If the particular workman on the job under consideration receives a different rate per hour for his labor, of course a different card 3 would be employed for use in connection with the indicator to compute the cost, *i. e.*, the length of time spent on a particular job multiplied by the rate per hour.

If the workman devoted so many days' time

and so many hours and minutes to a given job, the days' time could be ascertained from the table at the upper righthand corner of the card 3, to which would be added the hours and minutes.

Instead of having the indicator supporting block 9 and the indicator 13 arranged thereon, detachably and separately connected, I may form the grooves or kerfs 6 and 10 in the shape of a T, as shown in Fig. 7 and provide rollers 15 and 16 on the lower faces of the indicator 13 and the movable block 9 so that the parts 9 and 13 may be adjusted relative to each other and to the bed plate 1 by sliding the same in position. This will avoid the necessity of bodily lifting the parts 9 and 13 for purposes of adjustment and prevent loss of said parts by rendering it unnecessary to detach them during the operations of adjustment thereof.

While I have shown the bed or base plate 1 and the indicator supporting element 9 as being provided with grooves or kerfs leading from hour to minute scales whereby it is possible to adjust the supporting element 9 on the bed plate and the indicating element 13 on the supporting element 9 and hold them against accidental displacement, it is obvious that a bed plate 17 shown in Fig. 8, having a flat unkerfed surface provided with lines 18 would answer the same purpose as the grooves, and if desired, holes or openings 19 could be provided in the bed-plate 17 into which could be fitted projections 20 extending from the coöperating time of starting element 21 and in this way avoid accidental displacement of the parts.

The "time of starting" element may similarly be provided with openings 22 and lines 23 with which openings coöperate pins 24 on the "time of finishing" element 25 and which, as in the construction above referred to, carries the cost indicating scales and pointer on the end of its connected bar 26.

What I claim is:

1. In an apparatus of the character described, the combination of a base having hour and minute scales arranged at angles to each other, a movable starting time indicator angularly adjustable on said base and also having hour and minute scales arranged at angle to each other, a finishing time indicator arranged on said starting time indicator and capable of angular adjustment thereon, and a computing table containing numbers representing the cost of labor at a given rate per hour with which said finishing time indicator coöperates.

2. In an apparatus of the character described, the combination of a base having hour and minute scales arranged at angles to each other, a movable starting time indicator angularly adjustable on said base to indicate the time of beginning work, said indicator also having hour and minute scales

- arranged at angles to each other, a finishing time indicator arranged on said starting time indicator and capable of angular adjustment thereon to indicate the time of finishing the work, and a computing table containing numbers representing the cost of labor at a given rate per hour with which said finishing time indicator coöperates, said finishing time indicator being provided 5 with a minute deduction scale for indicating the total cost of labor less a given number of minutes to be deducted from the time lapsing between beginning and finishing the work.
- 10 3. In an apparatus of the character described, the combination of a base having hour and minute scales arranged at angles to each other, a starting time indicator angularly adjustable on said base to indicate the time of beginning work, said indicator also 20 having hour and minute scales, a finishing time indicator arranged on said starting time indicator and capable of angular adjustment to indicate the time of finishing the work, and a computing table containing 25 numbers representing the cost of labor at a given rate per hour with which said finishing time indicator coöperates, said indicator being provided with oppositely disposed deduction minute scales for the purposes de- 30 scribed.
- 15

In testimony whereof I hereunto affix my signature, this 22nd day of June, 1918.

CLYDE P. EVANS.
